DEMOUNTABLE PERSONNEL CAB FOR PICKUP TRUCKS

Jack T. Bell, 16304 SE. 16th St.,
Vancouver, Wash. 98664

Filed Sept. 17, 1971, Ser. No. 181,648

Term of patent 14 years

Int. Cl. D12—16

U.S. Cl. D14—3 J

FIG. 1 is a rear elevational view of a demountable personnel cab for pickup trucks showing my new design;

FIG. 2 is a front elevational view;

FIG. 3 is a right side elevational view;

FIG. 4 is a left side elevational view;

FIG. 5 is a top plan view; and

FIG. 6 is a bottom plan view.

I claim:

The ornamental design for a demountable personnel cab for pickup trucks, as shown.
